US0D1063821S

(12) **United States Design Patent** (10) **Patent No.:** **US D1,063,821 S**
(45) **Date of Patent:** **** Feb. 25, 2025**

(54) **BATTERY COVER**

(71) Applicant: **CPS Technology Holdings LLC**, New York, NY (US)

(72) Inventors: **Daryl C. Brockman**, Shorewood, WI (US); **James C. Douglass**, Newport Beach, CA (US)

(73) Assignee: **CPS Technology Holdings LLC**, New York, NY (US)

(**) Term: **15 Years**

(21) Appl. No.: **29/858,237**

(22) Filed: **Oct. 28, 2022**

(51) LOC (15) Cl. **13-02**

(52) U.S. Cl.

USPC **D13/103**; D13/121; D13/118; D13/156

(57) **CLAIM**

The ornamental design for a battery cover as shown and described.

DESCRIPTION

FIG. 1 is top perspective view of a battery cover;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines depict portions of the battery cover that form no part of the claimed design.

1 Claim, 6 Drawing Sheets
